Primary Examiner — Kimberly Barnes(74) *Attorney, Agent, or Firm* — Maschoff Brennan(57) **CLAIM**

The ornamental design for a cleaning robot, as shown and described.

DESCRIPTION

FIG. 2.1 is a front view of a cleaning robot, showing our new design;

FIG. 2.2 is a rear view thereof;

FIG. 2.3 is a left-side view thereof;

FIG. 2.4 is a right-side view of thereof;

FIG. 2.5 is a top view thereof;

FIG. 2.6 is a bottom view thereof; and,

FIG. 2.7 is a front perspective view thereof.

The broken lines shown in the views depict portions of the cleaning robot that form no part of the claimed design.

1 Claim, 6 Drawing Sheets(56)
